UNITED STATES PATENT OFFICE.

FRANK T. FOWLER, OF CHICAGO, ILLINOIS.

DESIGN FOR A BICYCLE-FRAME.

SPECIFICATION forming part of Design No. 25,078, dated January 21, 1896.

Application filed December 17, 1895. Serial No. 572,464. Term of patent 14 years.

To all whom it may concern:

Be it known that I, FRANK T. FOWLER, a citizen of the United States, residing at Chicago, Cook county, Illinois, have invented and produced a new and original Design for Bicycle-Frames, reference being had to the accompanying drawing, forming part hereof.

In the accompanying drawing, the figure represents a perspective view of my frame.

10 The leading feature of my design consists in the main portion provided with the curved parabolic-shaped central portion connected to the bifurcated portion.

A is the main portion, comprising the parts

a a, b b, c c, and d; B, a substantially parabolic-shaped central portion connected to the apex of the main portion by means of the bifurcated piece C, the whole presenting to the eye a harmonious and ornate figure, as illustrated in the drawing.

I claim—

The design for a bicycle frame herein shown and described.

FRANK T. FOWLER.
